and Perry & Norton of Albany, (aforesaid)

Letters Patent N°. 793. Dated May 20th. 1836.

The schedule referred to in these Letters Patent, and making
part of the same.

To whom it may concern:

Be it known that I, Samuel W. Gibbs, of
the City of Albany, State of New York, have produced
a new and original Ornamental Design for the plates
of a Hall and Parlor Stove; and I hereby declare that
the annexed drawings or delineations, forming part
of this specification are accurate delineations thereof: viz,
of the top plate, of the bottom and base as combined to-
gether of the body and cylinder as combined together, and
of a leg.

What I claim as my production and
desire to secure by Letters Patent is the combination and
arrangement of ornamental figures and forms as presen-
ted in the accompanying drawings or delineations, form-
ing together the ornamental design for the plates of
a Hall and Parlor Stove.
